UNITED STATES PATENT OFFICE.

FRANK M. CASTLEMAN, OF ROTHERHAM, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

POWER-OPERATED RAM.

1,407,253.

Specification of Letters Patent. Patented Feb. 21, 1922.

Application filed March 17, 1920. Serial No. 366,713.

To all whom it may concern:

Be it known that I, FRANK MASTERS CASTLEMAN, a subject of the King of Great Britain, residing at Rotherham, in the 5 county of Yorkshire, England, have invented a certain new and useful Improvement in Power-Operated Rams, of which the following is a specification.

This invention relates to power-operated 10 rams for railway systems and more particularly light railway track systems for mining tubs or trucks and the like, and has for its object to provide an improved arrangement of ram mechanism which shall be 15 specially applicable for the propulsion of vehicles of the above description past a given point in the railway track.

Arrangements have previously been proposed comprising a power-operated ram located 20 on the track, between two rails thereof, the movable stem or plunger of the ram being provided with an arm flexibly connected thereto and projecting upwards at a suitable angle to the axis of the ram itself so as 25 to be capable of engaging with a coupling hook on the vehicle.

According to the present invention a power-operated ram of the above general character is so constructed that fluid under 30 pressure is arranged to be supplied to or released from the ram casing on the inner side of the plunger, the space on the outer side of the plunger between the ram casing and the plunger stem or rod being arranged 35 to be permanently connected to a source of fluid under pressure.

According to a further feature of the invention, the extremity of the ram above referred to is adapted to engage with the axle 40 of the tub or truck passing over the ram so that upon such engagement being effected and the ram actuated by pneumatic or other forms of power, the thrust of the plunger will be transmitted through the projecting 45 arm to the axle of the vehicle which will thereby receive an impulse in the desired direction.

The invention is illustrated in the accompanying drawings of which:-

50 Figure 1 is a view in side elevation of a portion of a light railway track provided with ram mechanism constructed in accordance with one form of the invention.

Figure 2 is a view in longitudinal section

of the power-operated ram shown in Figure 1;

Figure 3 being a view in side elevation of the head of the ram on an enlarged scale.

Figure 4 is a view in transverse section showing the ram in position between the 60 rails of the track.

Referring now to the drawings it will be seen that the power-operated ram comprises a cylindrical casing 1 located horizontally midway between the track rails 2 and of a 65 length corresponding to the stroke or travel of the ram which it is desired to obtain. One end of the casing 1 is provided with a head 3 containing the inlet and exhaust valves for the admission of fluid under pressure for operating the ram, these valves being preferably arranged to be operated by any suitable type of electro-magnetically actuated mechanism not shown in the drawings. The plunger or piston of the ram 70 is indicated at 4 and may be of any preferred construction, a plunger rod or stem 5 extending beyond the opposite end of the casing 1 to that terminating in the head 3 and being provided with a suitable gland or 75 bushing indicated at 6. The outer end of the plunger stem 5 is provided with a cross head 7 on which is pivotally mounted as indicated at 8 one end of a driving arm—serv- 80 ing to transmit the thrust of the ram to a vehicle axle 10 with which it engages, the pivotal connection of the driving arm 9 and the cross head 7 being horizontally arranged so that the arm 9 is free to rotate to a limited extent in the vertical plane containing the 85 axis of the ram. The upward movement of the driving arm 9 relative to the cross head 7 is limited by a stop 11 formed on the cross head itself and the driving arm 9 is normally maintained in its upward inclined position, 90 as shown in Figures 1 and 3, by means of a suitable spring 12, the upper end of which abuts against the upper portion of the cross head, as indicated at 13, the lower end of the spring 12 abutting against a lag or tail 14 95 formed on the driving arm 9 beyond its pivot 8. The outer end 13 of the driving arm 9 is slightly curved to a suitable form for the purpose of engaging the axle 10 of a 100 tub or truck 16 as clearly shown in Figure 3.

The weight of the stem or rod 5 of the plunger 4 and of the cross head 7 connected

thereto is arranged to be carried by a pair of rollers 17 (see Figure 4) rotatably mounted upon the pivot 8 for the driving arm 9, which rollers operate on runways 18 mounted 5 upon the track midway between the track rails 2.

The ram casing 1 is secured in position on the track by a clamping or mounting device indicated at 19 in Figure 1 which 10 forms an abutment withstanding the thrust exerted by the ram during operation.

As stated above, the operation of the ram is preferably effected by fluid under pressure and for this purpose the interior of the ram 15 casing 1 is adjacent to the packing gland 6, arranged to be in communication with a source of fluid under pressure by means of a pipe 20 as shown in Figure 2. The opposite face of the plunger 4 is arranged to be 20 supplied with fluid under pressure through a suitable valve located within the head 3 communicating with a chamber 21 formed in the head 3. Fluid under pressure is also arranged to be released from the chamber 21 25 through a suitable release valve, both these valves being of any suitable type, preferably electro-magnetically actuated.

The operation of the ram mechanism above described is as follows:—

Owing to the resilient mounting of the 30 driving arm 9 a truck or other vehicle 16 can pass freely over the driving arm in one direction, each axle 10 of the truck depressing the driving arm 9 against the action of the spring 12. After the axle has passed 35 over the end 15 of the driving arm, the latter rises under the action of the spring 12 to a position limited by means of the stop 11. In this position the end 15 of the driving 40 arm 9 is at such a height above the track rails 2 as to engage with the axle 10 of the truck as clearly shown in Figure 3. In order to drive the truck forward, fluid under pressure is now admitted to the chamber 21 45 through the inlet valve communicating therewith, and the pressure thus produced in the rear part of the ram casing 1 acting on the full area of the ram plunger 4 forces the latter forward, this forward motion being opposed by the resistance of the truck 16 to 50 movement and by the pressure of the fluid supplied through the pipe 20. This latter pressure, however, only acts upon a reduced area of the plunger 4 constituted by the difference between the full area of the plunger and the cross sectional area of the plunger rod or stem 5. The plunger 4 and its stem 5 are consequently driven forward, movement being thus imparted through the cross 55 head 7 and the driving arm 9 to the axle 10 of the truck 16. After the plunger 4 has completed its full range of travel, the truck 16 will be carried forward under its own momentum and the plunger 4 may be with- 60 drawn to effect the propulsion of a second 65

truck or vehicle. This return movement of the plunger is effected by operating the outlet valve for the chamber 21, the fluid under pressure contained in the ram casing 1 being thereby permitted to escape to the atmosphere. Under these conditions the plunger 4 moves backwards under the pressure of the fluid supplied through the pipe 20 and the stem or rod 5 of the plunger and cross head 7 of the driving arm correspondingly return to their retracted position.

The improved ram mechanism of the invention is particularly suitable for use in connection with unloading and loading gear for the hoisting plant in collieries and other mining installations, but may also be utilized in connection with other track systems where a propelling impulse is required to be transmitted to vehicles at a particular point in the track.

The constructional details of the ram and driving arm mechanism may obviously be modified in accordance with the conditions to be met without exceeding the scope of the invention.

Having now described my invention, what I claim as new and desire to secure by Letters Patent, is:—

1. Power-operated ram mechanism for railway or tramway systems of the kind 95 comprising a power-operated ram located on the railway track, the movable stem or plunger of the ram being provided with an arm flexibly connected thereto projecting upwards at a suitable angle to the axis of the 100 ram itself and adapted to engage with the vehicle to be propelled in which fluid under pressure is arranged to be supplied to or released from the ram casing on the inner side of the plunger, the space on the outer side 105 of the plunger between the ram casing and the plunger stem or rod being arranged to be permanently connected to a source of fluid under pressure, for the purpose specified.

2. Power operated ram mechanism of the 110 kind claimed in claim 1 in which the end of the driving arm is adapted to engage with the axle of the vehicle to be propelled, for the purpose specified.

3. Power ram mechanism for railways 115 comprising a casing located in the trackway, a piston movable in said casing and provided with a stem projecting from the casing, means for constantly supplying fluid pressure to said casing on one 120 side of the piston to retract the piston and stem, and means for at times connecting the casing on the other side of the piston with a source of fluid pressure to project the piston and stem.

4. Power ram mechanism for railways comprising a casing located in the trackway, a piston movable in said casing and provided with a stem projecting from the casing, means for biasing said piston 130

and stem to a retracted position, and means for at times admitting fluid pressure to said casing in the rear of the piston to project the piston and stem in opposition to 5 said biasing force.

5. Power ram mechanism for railways, comprising a casing horizontally disposed in the trackway, a piston movable in said casing and provided with a stem projecting 10 from the casing, a driving arm pivotally attached to the outer end of said stem to move into and out of the path of cars on the trackway, and a spring for biasing said driving arm to such position that it will engage with 15 a car on the trackway.

6. Power ram mechanism for railways, comprising a casing horizontally disposed in the trackway, a piston movable in said casing and provided with a stem projecting from the casing, a driving arm pivotally attached to the outer end of said stem to move into and out of the path of cars on the trackway, a spring for biasing said arm to such position that it will engage with a car on the trackway, and a stop for limiting the upward movement of said arm under the influence of said spring. 20 25

In witness whereof I have hereunto set my hand.

F. M. CASTLEMAN.
